OIL WELL PUMPING UNIT

Frederick A. Gruetjen, Milwaukee, Wis., assignor
to A. O. Smith Corporation, Milwaukee, Wis.,
a corporation of New York

Application April 28, 1941, Serial No. 390,782

16 Claims. (Cl. 103—45)

This invention relates to an oil well pumping unit and more particularly to a pump in which a reciprocating crude oil pump is operated by a reciprocating fluid motor driven by pressure fluid from a power pump. In this type of pump the pressure fluid is preferably clean oil and has a closed circuit comprising a reservoir, a power pump, a control valve, and the fluid motor from which it returns to the reservoir. The power pump is normally driven by an electric motor, and the entire unit is submerged beneath the crude oil at the bottom of the well.

In this type of unit there has been considerable difficulty in loss of power fluid, and also in contamination of the power fluid by sand and other constituents from the crude oil.

The principal object of the present invention is to maintain the required quantity of clean power fluid over a substantial period of operation of the pump.

A more specific object is to prevent loss of power fluid.

Another object is to prevent injurious contamination of the power fluid and to provide for its replenishment by clean fluid in case of loss.

In accordance with the invention the circuit of the power fluid is hermetically sealed with the exception of the opening through which the fluid motor piston operates to drive the crude oil pump, and suitable packings are provided on the piston rod with a bleeder through the housing from between two groups of packing to the reservoir for power fluid.

In another phase of the invention a second bleeder is employed between two groups of packing at the lower end of the piston rod near the crude oil pump, leading to the well space outside of the housing.

A pump employing the principles of the invention is illustrated in the accompanying drawing in which:

Figure 1 is a schematic longitudinal section showing the unit in a well, and

Fig. 2 is a longitudinal central section through the pertinent part of the unit illustrating the invention.

Referring to Figure 1 the pumping unit comprises a housing 1 suspended by a delivery pipe 2 or cable in a well 3, the housing usually being entirely submerged in crude oil 4 at the bottom of the well.

The housing contains an electric motor 5 at the top, an oil reservoir 6, a power pump 7, a valve control 8 for the fluid motor, a fluid motor 9 and a crude oil pump 10.

Figure 2 shows the detail construction of the packing intermediate the fluid motor 9 and crude oil pump 10. In it the fluid motor 9 and crude oil pump 10 are shown as having a common piston rod 11.

The upper end of the housing 1 is sealed so that there is no chance for power fluid to escape except downwardly along piston rod 11 and into the crude oil pump 10.

10 In carrying out the present invention, it is preferable to employ four sets of packings around the piston rod, as well as sand scrapers 12 at the lower end for preventing sand from following upward along the rod from the crude oil pump.

15 The packings are made up of annular rings of impregnated fabric or molded oil proof composition pressed together between spring metal rings with their edges directed against the piston rod at an angle. The lower two sets 13 and 14 of packing have their edges extending downwardly and inwardly against the piston rod, while the upper two sets 15 and 16 of packing have their edges extending upwardly and inwardly against the piston rod. This type of packing and arrangement has been found to be most effective in preventing upward leakage of crude oil from the crude oil pump and downward leakage of clean power oil from the fluid motor.

20 In order to catch any clean power oil which may leak downwardly past the upper packing 15, a small annular recess 17 is provided in the packing housing facing the piston rod and between packings 15 and 16. This recess 17 is connected by a passage 18 to the reservoir 6 either above or below the level of oil therein. Any build up of pressure of oil in the recess 17 from the fluid motor will tend to force the leakage oil back up into the reservoir.

25 In this system packing 15 works to prevent leakage of oil from the motor in which very high fluid pressures are used, while packing 16 works only to prevent leakage by reason of the pressure developed by the head of oil in reservoir 6.

30 Should there be a tendency for power fluid to leak past packing 16, an additional feature of the present invention provides a counter pressure of fluid below the packing equal to or greater than that normally above it. This is obtained by the pressure of crude oil tending to leak past packings 13 and 14 from the crude oil pump. This pressure would normally be equal

to the head of oil in the delivery pipe 2, extending the full depth of the well.

Since this counter pressure would be so great as to force crude oil past the packings and effect complete filling of the housing, with possible danger of contamination, a second feature of the invention comprises the providing of an annular recess 19 in the packing housing facing the piston rod between packings 13 and 14 and connecting the recess with the space in the well outside of the housing by means of a passage 20. In this way the pressure of crude oil on the packing 14 will be no greater than the head of oil in the well as all oil leaking past the packing 13, due to the head of oil in the delivery pipe 2, is vented at port 20.

A filter 21 or other means may be provided in passage 20 to keep any oil which flows in from the well through the passage free from sand or to entirely prevent the flow of oil inwardly. Normally, the leakage of oil past packing 13 due to the great pressures developed in the crude oil pump will insure that dirty oil will not seep in through passage 20. The head of oil in the well, however, will normally be sufficient to maintain a fluid pressure below packings 14 and 16 greater than that above, and consequently there will be no tendency for leakage of power oil downwardly past the packings.

The port 20 might be connected to bleed a space between packings 14 and 16 or either packing 14 or 16 or, in some instances, both might be eliminated. Any tendency for leakage of crude oil into the power oil system from below merely raises the pressure in the reservoir 6 until a balance is reached that prevents further leakage. Where it is desired to retain a gas space in the reservoir, the latter may be charged under pressure sufficient to prevent any infiltration of crude oil into the system.

The detail construction of the packings herein illustrated is set forth and claimed in an application, Serial Number 390,783 filed on even date herewith by the present inventor. An improved construction for carrying out the present invention is illustrated and claimed in application, Serial No. 390,781, filed on even date herewith by the present inventor.

Various embodiments of the invention may be employed within the scope of the accompanying claims.

The invention is claimed as follows:

1. In an oil well pumping unit, a reciprocating crude oil pump disposed vertically at the bottom of the well, a reciprocating fluid motor disposed above the pump, a common piston rod connecting the pump and motor for driving the former by the latter, a substantially closed circuit for power fluid to operate said motor, packing means encircling said piston rod between said motor and pump to substantially prevent leakage of power fluid along said rod from the motor, means for returning leakage power fluid from an intermediate point in said packing means to the power fluid circuit on the exhaust side of the motor, and means including said crude oil pump for maintaining a fluid pressure below said packings which is at least equal to the fluid pressure of said leakage power fluid to prevent leakage of the latter beyond said intermediate point in the packing.

2. In an oil well pumping unit, a reciprocating crude oil pump disposed vertically at the bottom of the well, a reciprocating fluid motor disposed above the pump, a common piston rod

connecting the pump and motor for driving the former by the latter, a substantially closed circuit for power fluid to operate said motor, packing means encircling said piston rod between said motor and pump to substantially prevent leakage of power fluid along said rod from the motor, means for returning leakage power fluid from an intermediate point in said packing means to the power fluid circuit on the exhaust side of the motor, and means for bleeding leakage of crude oil from said pump from an intermediate point in said packing below said first named intermediate point to the space in the well outside of the unit.

3. In a device of the class described, a fluid motor having a reciprocating piston with a piston rod, a power pump for supplying fluid under pressure to said motor, a reservoir for power fluid for receiving the exhaust from said motor and supplying fluid to said power pump, an electric motor for driving said power pump, a hermetically sealed housing enclosing the above named elements and through the end wall of which the piston rod of said fluid motor reciprocates, packing means encircling said piston rod, and means in said housing for returning power fluid which may have leaked past said packing to the reservoir.

4. In a device of the class described, a fluid motor having a reciprocating piston with a piston rod, a power pump for supplying fluid under pressure to said motor, a reservoir for power fluid for receiving the exhaust from said motor and supplying fluid to said power pump, an electric motor for driving said power pump, a hermetically sealed housing enclosing the above named elements and through the end wall of which the piston rod of said fluid motor reciprocates, packing means encircling said piston rod, an annular recess in the packing housing wall intermediate sections of packing, and a passage in the wall of said housing and connecting said recess to the reservoir.

5. In a device of the class described, a fluid motor having a reciprocating piston with a piston rod, a power pump for supplying fluid under pressure to said motor, a power fluid reservoir for receiving the exhaust from said motor and supplying fluid to said power pump, an electric motor for driving said power pump, a hermetically sealed housing enclosing the above named elements and through the end wall of which the piston rod of said fluid motor reciprocates, packing means encircling said piston rod, an annular recess in the packing housing wall intermediate sections of packing, a passage connecting said recess to the reservoir, and means to maintain a fluid pressure below said packing tending to balance the pressure of fluid in said recess to prevent loss of power fluid.

6. In a device of the class described, a fluid motor having a reciprocating piston with a piston rod, a power pump for supplying fluid under pressure to said motor, a reservoir for power fluid for receiving the exhaust from said motor and supplying fluid to said power pump, an electric motor for driving said power pump, a hermetically sealed housing enclosing the above named elements and through the end wall of which the piston rod of said fluid motor reciprocates, said reservoir having a gas space above the fluid level therein and in which the gas is charged under a predetermined pressure, packing means encircling said piston rod, means for returning power fluid which may have leaked past said packing to

the reservoir, and means to maintain a fluid pressure below said packing tending to balance the pressure in said reservoir.

7. In a device of the class described, a fluid motor having a reciprocating piston with a piston rod, a power pump for supplying fluid under pressure to said motor, a reservoir for power fluid for receiving the exhaust from said motor and supplying fluid to said power pump, an electric motor for driving said power pump, a hermetically sealed housing enclosing the above named elements and through the end wall of which the piston rod of said fluid motor reciprocates, said reservoir having a gas space above the fluid level therein and in which the gas is charged under a predetermined pressure, packing means encircling said piston rod, means for returning power fluid which may have leaked past said packing to the reservoir, and a passage connecting a lower intermediate point in the packing to the outside well space to relieve the pressure from below the packing due to the crude oil pump.

8. In a device of the class described, a fluid motor having a reciprocating piston with a piston rod, a power pump for supplying fluid under pressure to said motor, a reservoir for power fluid for receiving the exhaust from said motor and supplying fluid to said power pump, an electric motor for driving said power pump, a hermetically sealed housing enclosing the above named elements and through the end wall of which the piston rod of said fluid motor reciprocates, packing means encircling said piston rod, means for returning power fluid which may have leaked past said packing to the reservoir, and a passage connecting a lower intermediate point in the packing to the outside well space to relieve the pressure from below the packing due to the crude oil pump.

9. In an oil well pumping unit, a crude oil pump disposed vertically at the bottom of the well, a fluid motor disposed above the pump, a driving connection between said motor and pump having packing means to prevent intermingling and leakage of power fluid and crude oil, a substantially closed circuit for power fluid to operate said motor, said packing being divided and having intermediate bleeder means for returning leakage power fluid to the power fluid circuit, and means for supplying to said power fluid circuit clean crude oil to maintain the supply of power fluid.

10. In an oil well pumping unit disposed at the bottom of the well, a crude oil pump, a fluid motor connected to drive said pump, a closed circuit for power fluid to drive said motor, a packing for the connection between the motor and pump subjected at one end to the pressure of said power fluid in the motor intake and at the other end to the pressure of the crude oil in the pump exhaust, and means intermediate the ends of said packing for relieving leakage fluid from said pressures.

11. In an oil well pumping unit disposed at the bottom of the well, a crude oil pump, a fluid motor connected to drive said pump, a closed circuit for power fluid to drive said motor, a packing for the connection between the motor and pump subjected at one end to the pressure of said power fluid in the motor intake and at the other end to the pressure of the crude oil in the pump exhaust, said packing being divided and having a passage connecting an intermediate recess therein to the exhaust side of said motor.

12. In an oil well pumping unit disposed at the bottom of the well, a crude oil pump, a fluid motor connected to drive said pump, a closed circuit for power fluid to drive said motor, a packing for the connection between the motor and pump subjected at one end to the pressure of said power fluid in the motor intake and at the other end to the pressure of the crude oil in the pump exhaust, said packing being divided and having a passage connecting an intermediate recess therein to the intake side of said crude oil pump.

13. In an oil well pumping unit disposed at the bottom of the well, a crude oil pump, a fluid motor connected to drive said pump, a closed circuit for power fluid to drive said motor, a packing for the connection between the motor and pump subjected at one end to the pressure of said power fluid in the motor intake and at the other end to the pressure of the crude oil in the pump exhaust, said packing being divided and having passages connecting an intermediate point therein to the exhaust side of said motor and the intake side of said pump.

14. In a deep well pumping unit having a reciprocating pump driven by a reciprocating hydraulic motor by means of a piston rod common to both, means for preventing loss of power fluid for driving said motor and of admixture of crude oil with the power fluid, comprising a series of packings surrounding said piston rod and disposed to prevent the leakage of crude oil along the rod from said pump and the leakage of power fluid along the rod from said motor, a take-off for crude oil which may leak past the set of packing nearest the pump, a similar take-off for power fluid which may leak past the set of packing nearest the motor, there being at least one set of packing between the two take-offs, means to return the crude oil from said crude oil take-off to the main body of crude oil, and means to return the power fluid from said power fluid take-off to the main body of power fluid.

15. In a deep well pumping unit having a reciprocating pump driven by a reciprocating hydraulic motor by means of a piston rod common to both, means for preventing loss of power fluid for driving said motor and of admixture of crude oil with the power fluid, comprising a series of packings surrounding said piston rod and disposed to prevent the leakage of crude oil along the rod from said pump and the leakage of power fluid along the rod from said motor, a take-off for crude oil which may leak past the set of packing nearest the pump, and a similar take-off for power fluid which may leak past the set of packing nearest the motor, there being at least one set of packing between the two take-offs.

16. In a deep well pumping unit having a reciprocating pump driven by a reciprocating motor by means of a piston rod, means for preventing fluid being pumped from leaking along the piston rod to the motor, comprising a series of packings surrounding said piston rod and disposed to prevent the leakage of fluid therealong from the pump, a take-off for fluid which may leak past the first set of packing nearest the pump, and means to return the fluid from said take-off to the main body of fluid being pumped.
